COIN OPERATED VENDING MACHINE

Clare E. Hodgman, Mamaroneck, N.Y., assignor to The Vendo Company, Kansas City, Mo., a corporation of Missouri

Application December 1, 1958, Serial No. 53,593

Term of patent 14 years

(Cl. D52—3)

Fig. 1 is a front perspective view of a coin operated vending machine, showing my new design;

Fig. 2 is an enlarged face view of the coin slot panel of the vending machine;

Fig. 3 is an enlarged, detailed, sectional view of the coin slot panel taken on line 3-3 of Fig. 2; and

Fig. 4 is an enlarged, sectional view of the coin slot panel, taken on line 4-4 of Fig. 2.

The dominant features of my new design reside in the coin slot panel shown in solid lines in the drawing.

I claim:

The ornamental design for a coin operated vending machine, as shown and described.
